H. W. LE FEVRE,
HOT WATER AND AIR TANK FOR DENTISTS' USE.
APPLICATION FILED JUNE 14, 1915.

1,209,599.

Patented Dec. 19, 1916.

UNITED STATES PATENT OFFICE.

HARRY W. LE FEVRE, OF DENVER, COLORADO.

HOT WATER AND AIR TANK FOR DENTISTS' USE.

1,209,599.

Specification of Letters Patent.

Patented Dec. 19, 1916.

Application filed June 14, 1915. Serial No. 33,925.

To all whom it may concern:

Be it known that I, HARRY W. LE FEVRE, a citizen of the United States, residing in the city and county of Denver and State of Colorado, have invented certain new and useful Improvements in Hot Water and Air Tanks for Dentists' Use; and I do declare the following to be a full, clear, and exact description of the invention, such as will 5 enable others skilled in the art to which it appertains to make and use the same, reference being had to the accompanying drawings, and to the characters of reference marked thereon, which form a part of this 10 specification.

My invention relates to improvements in tanks adapted to supply hot water and hot or warm air under pressure, being more especially adapted for use by dentists. The 15 necessity for the use of warm water and air by dentists for spraying the gums and teeth for obvious reasons, during their work is well understood. Heretofore so far as I am aware no single apparatus has been available for supplying both air and water for 20 this purpose.

My object is to provide a single apparatus, readily accessible for supplying both warm air and water under the necessary pressure, 25 so that all that will be necessary in order to change from one to the other, is to lay down one nozzle and pick up another these nozzles being respectively connected with flexible pipes leading from the tank.

In my improved construction the tank 30 contains water which is kept at the desired temperature by means of a Bunsen burner which is suitably connected with a source of gas supply, the burner being suitably 35 connected with the bottom of the tank. The burner stand as illustrated in the drawing forms a support for the tank. It is evident, however, that the water in the tank may be kept at the proper temperature through the 40 agency of any suitable heat source. The water is removed from the tank by air pressure supplied by connecting the upper extremity of the tank chamber with a source of air under pressure, the water escaping 45 from the tank through a pipe having its inner extremity which is open, located close to the bottom of the tank, the upper extremity of the said pipe protruding from the top of the tank and with which a flexible 50 tube equipped with a suitable nozzle, is con-

nected. Also located within the tank and surrounded by the water therein, is a coil of pipe whose extremities protrude also from the top of the tank and are respectively connected with flexible tubes, one of which 55 leads to a source of air under pressure, while the other is equipped with a nozzle for delivering air to the mouth. This air is warmed or sufficiently heated for the purpose, by passing through the coil of pipe 60 which is submerged by the hot water in the tank as heretofore explained. Each metal pipe extremity where it extends above the tank, is equipped with a valve for regulating the supply of air or water as the case may 65 be. The tank is further equipped with an inlet pipe connected with its upper extremity and also equipped with a tube leading to a source of water supply.

Having briefly outlined my improved construction I will proceed to describe the same in detail, reference being made to the accompanying drawing in which is illustrated an embodiment thereof.

In this drawing which is a central vertical 70 section taken through the apparatus, let the numeral 5 designate the tank which as shown is cylindrical in shape and whose bottom is equipped with a depending cone shaped bracket 6 having a bottom opening 7 75 adapted to receive a Bunsen burner 8 which is connected with the bracket by means of a set bolt 9. The burner is mounted in a socket 10 formed in the upper extremity of a supporting base 12. A pipe 13 is connected with this base for supplying gas to the burner the latter being equipped with perforations 14 through which atmospheric air enters. The bracket 6 is provided with openings 15 through which the necessary air 80 is brought into contact with the gas as it leaves the upper extremity of the burner, for combustion purposes.

The top of the tank is provided with a relatively large interiorly threaded opening 100 16 into which is screwed a closure plate or cap 17 which is formed relatively heavy, the top of the tank where the opening is located being reinforced as shown at 18 for the purpose. The screw cap 17 is provided 105 with a top flange 19 overlapping the upper extremity of the reinforced part 18, a gasket 20 being located between the cap and the part 18 in order to form a fluid tight joint. This screw cap 17 is provided with 110

openings 21, 22 and 23 through which are passed bushings 24, 25 and 26 respectively. These bushings extend above the top of the tank and are respectively connected with coupling sleeves 27, 28 and 29, which are supplied with glands 30, thus constituting stuffing box constructions whereby fluid tight joints are formed. Passing through these bushings and extending above the same are pipes 31, 32 and 33 respectively, the same being respectively equipped with valves 74, 75 and 76 whose movable members are provided with hand pieces to facilitate manipulation. With the upper extremities of these pipes are connected flexible tubes 35, 36 and 37 respectively. The outer extremity of the tube 35 is equipped with an instrument 38 for spraying air into the mouth, while the corresponding extremity of the tube 36 is provided with an instrument 39 for spraying water into the mouth. The outer extremity of the tube 37 is connected with a source of air under pressure (not shown).

25 The top of the tank beyond the screw cap 17 is provided with openings 40 and 41 through which are passed bushings 42 and 43 respectively, to whose outer extremities are applied coupling sleeves 44 and 45 which 30 coöperate with glands 46 to form fluid tight joints around pipes 47 and 48 which pass through the said bushings and extend above the coupling sleeves where the said pipes are equipped with valves 49 and 50 respectively.

35 Connected with the upper extremities of these pipes are flexible tubes 51 and 52. The outer extremity of the pipe 51 leads to a source of water supply (not shown); while the corresponding extremity of the tube 52 is in communication with a source of air under pressure (not shown).

The inner extremity of the pipe 47 which supplies water to the tank, terminates a short distance below the top of the tank, 45 which is also true of the pipe 48 which supplies air under pressure for expelling the water 53 from the tank. The pipe 32 extends downwardly into the tank, its inner extremity being open and terminating a short distance above the bottom of the tank, sufficient space being left to permit the water to enter this extremity of the pipe freely for purposes of escape when the valve 75 is open for the purpose, and air is supplied 55 above the water through the pipe 48, which is accomplished by opening the valve 50.

The inner extremity of the pipe 33 merges into a coil 54 which is submerged by the water 53 when the tank is filled. The lower 60 convolution of this coil merges into an upwardly extending pipe 55 which merges into the exterior pipe member 31 through which the air passes to the instrument 38 as heretofore explained, assuming that the valve 74 is open. In other words the air utilized by

the instrument 38, enters the pipe coil 54 by way of the pipe 33 through the tube 37, and after traversing the coil passes out of the tank through the pipe 55, the external pipe member 31 and the tube 35 to the said instrument. 70

The cap 17 of the tank is also provided with an opening 56 into which is threaded a bushing 57 which is perforated, the outer extremity of the perforation being closed 75 by a valve 58 normally held in the said position by a spring 59 one extremity of which engages the valve while the opposite extremity engages the upper end of a casing 60 which has a threaded connection with the 80 upper extremity of the bushing 57, the casing being perforated as shown at 61 whereby its chamber is placed in communication with the atmosphere.

Upon one side of the tank is mounted a 85 gage glass 62 while upon the opposite side is mounted a thermometer 63, the lower extremity of the thermometer extending into an exteriorly located receptacle 64 which is mounted upon the tank and filled with water 90 and by virtue of the fact that the receptacle is mounted upon the tank whereby the wall of the tank forms one of the walls of the receptacle, the water within the latter is maintained at the same temperature as that 95 within the tank. Hence the thermometer whose lower portion is submerged in the water of the receptacle, is very sensitive and accurately indicates at all times the temperature of the water in the tank. 100

The tank is further provided with a faucet 65 which is connected with the lower portion thereof. The upper extremity of the tank is equipped with a pressure gage 66.

From the foregoing description the use 105 and operation of my improved apparatus will be readily understood. The necessary water is supplied to the tank through the tube 51 and the pipe 47. When it is desired to use water from the tank, the valve 110 50 is opened whereby the water 53 is placed under pressure. Then as soon as the valve 75 is opened, the water passes to the instrument 39 which is controlled by the operator whereby the water is allowed to escape 115 whenever desired, said water having the necessary pressure due to the entrance of air under pressure through the valve 50 at the top of the tank as heretofore explained. When it is desired to use air in the mouth 120 of the patient, the valves 76 and 74 are opened, and the air passes from the source of supply through the tube 37, the pipe 33, the coil 54, the pipes 55 and 31 and the tube 35 to the instrument 38. The pressure of this 125 air is due to the fact that the pipe 37 is connected with an air tank or receptacle containing air under the necessary pressure. The instrument 38 is of such character that the air is only allowed to escape at the will 130

of the operator. As the water 53 within the tank is kept at the desired temperature by the employment of any desired source of heat, (a Bunsen burner 8 being shown), the 5 air is heated to the desired temperature while passing through the coil 54 and the pipe 55. It will thus be observed that the water within the tank performs the double function of supplying the instrument 39, 10 and also that of raising the air to the necessary temperature while passing through the coils and pipe 54 and 55 respectively within the tank.

Having thus described my invention, what 15 I claim is,—

1. A combined apparatus for supplying warm water and warm air, comprising a tank adapted to contain water, a coil of pipe therein adapted to be submerged by the 20 water, the extremities of the pipe passing through the top of the tank, and respectively connected with a source of air under pressure, and an instrument for controlling the escape of air, a conduit in communication 25 with the water of the tank at one extremity and connected at its opposite extremity with an instrument for controlling the escape of water, and means for introducing air under pressure into the tank above the water.

2. Apparatus of the class described comprising a tank adapted to contain water, three pipes passing through the top of the tank, means for forming fluid tight joints around the said pipes, a coil of pipe within the 35 tank, two of said pipes forming the terminals of said coil and being respectively in communication with a source of air under pressure and an instrument for dispensing air after passing through the coil, the third 40 pipe being in communication with the water of the tank at one extremity and at the opposite extremity with an instrument for dispensing water, and means carried by one of said coil terminals for controlling 45 the passage of air.

3. Apparatus of the class described comprising a tank adapted to contain water, three pipes passing through the top of the tank, a coil of pipe within the tank, two of 50 said pipes forming the terminals of said coil and being respectively in communication with a source of air under pressure and an instrument for dispensing the air after passing through the coil, the third pipe being in 55 communication with the water of the tank at one extremity and at the opposite extremity with an instrument for dispensing water, and means for introducing air under pressure into the top of the tank above the 60 water.

4. Apparatus of the class described comprising a tank adapted to contain water, three pipes passing through the top of the tank, a coil of pipe within the tank, two of 65 said pipes forming the terminals of said

coil, these terminals being respectively in communication with a source of air under pressure and an instrument for dispensing the air after passing through the coil, the third pipe being in communication with 70 the water of the tank at one extremity and at its opposite extremity with an instrument for dispensing water, and valve-controlled means for introducing air under pressure to the top of the tank above the water. 75

5. Apparatus of the class described comprising a tank adapted to contain water, three pipes passing through the top of the tank, two of said pipes forming the terminals of the said coil and being respectively 80 in communication with a source of air under pressure and an instrument for dispensing the air after passing through the said coil, the third pipe being in communication with the water of the tank at one extremity and at the opposite extremity with an instrument for dispensing water, valve-controlled means for introducing air under pressure to the tank above the water, and valve-controlled means for introducing water to 90 the tank.

6. Apparatus of the class described comprising a tank adapted to contain water, three pipes passing through the top of tank, a pipe member within the tank, two of said 95 pipes forming the terminals of said pipe member and being respectively in communication with a source of air under pressure and an instrument for dispensing the air after passing through the said pipe member, 100 the third pipe being in communication with the water of the tank at one extremity and at the opposite extremity with an instrument for dispensing the water, and means for introducing air under pressure to the top of 105 the tank.

7. Apparatus of the class described comprising a tank adapted to contain water, three pipes passing through the top of the tank, a pipe member within the tank, means 110 for supplying the tank with water whereby said pipe member is submerged, two of said pipes forming the terminals of said pipe member and being respectively in communication with a source of air under pressure 115 and an instrument for dispensing the air after passing through said pipe member, the third pipe being in communication with the water of the tank at one extremity and at the opposite extremity with an instrument 120 for dispensing water.

8. Apparatus of the class described comprising a tank adapted to contain water, three pipes passing through the top of the tank, a pipe member within the tank, means 125 for supplying the water to the tank whereby said member is partially submerged, means for maintaining the water in the tank at the proper temperature, a temperature indicating device exteriorly mounted on the tank, 130

an exteriorly located water containing receptacle also mounted on the tank, the wall of the latter forming one wall of the said receptacle, the temperature indicating device being partially submerged by the water within the said receptacle, two of said pipes forming the terminals of said pipe member and being respectively in communication with a source of air under pressure and an instrument for dispensing the air after passing through the pipe member, the third pipe

being in communication with the water of the tank at one extremity and at the opposite extremity with an instrument for dispensing water.

15

In testimony whereof I affix my signature in presence of two witnesses.

HARRY W. LE FEVRE.
